BOWLING BALL JIG

John R. Denisco, 327 Salem St., West Pittston, Pa.
Filed Dec. 28, 1961, Ser. No. 162,787
9 Claims. (Cl. 77—63)

This invention relates to a jig for adjustably positioning a bowling ball under a stationary drill and in particular to a jig of improved construction which permits the drilling of a wide variety of finger and thumb holes without removing the ball from the jig.

Jigs for the general purpose of adjustably positioning a bowling ball under a drill are known. Conventionally known jigs provide for the clamping of the ball and for rotational movement of the same within the jig in order that the thumb and finger holes may be drilled at desired distances from each other and at desired angles with respect to a radius of the ball drawn through the hole at the surface of the ball. The former dimension is generally called the span of the holes and the latter is generally called the pitch.

These known jigs suffer from the disadvantage that the means for clamping the ball in the jig often is of such size and shape as to hinder the operation in making further adjustments and in lowering the drill to form the holes. Specifically conventional jigs generally clamp the ball by means of a ring of smaller diameter than the ball which rests on top of the ball and which is secured by means of various screw-type latches. The ring, or other ball-engaging structure, and the necessary latches often extend upwardly and outwardly to such an extent as to interfere with the operators' movements. In some cases the diameter of the ring may be so small that holes having a large span therebetween cannot be drilled without unclamping the ball and rotating it within the jig. In addition the ring and screw-type latches are bulky and require considerable time for their operation.

Another disadvantage of conventional jigs lies in their inability to permit the pitch of the holes to be adjusted in a fore and aft direction and in a side to side direction without repositioning the ball within the clamping means.

The jig of the present invention overcomes these disadvantages by providing a jig with a ball-holding device which clamps the ball only along a narrow circumferential portion thereof and by providing a jig which permits the ball to be rotated about three different axes and moved laterally whereby holes of fore and aft and side to side pitch can be drilled without changing the position of the ball in the clamping means.

It is therefore a primary object of the present invention to provide a bowling ball jig which permits the position of the ball to be rapidly and easily adjusted for the drilling of holes having preselected span, fore and aft pitch and side to side pitch without unclamping the ball from the jig.

It is a further object of the present invention to provide a jig for a bowling ball having a ball-holding means which exposes a maximum working surface of the ball.

The invention will be more fully understood from a reading of the following description of a preferred embodiment of a bowling ball jig when taken in conjunction with the drawings in which:

FIGURE 1 is a front elevational view of a bowling ball jig embodying the principles of the present invention;

FIGURE 2 is a front elevational view of the bowling ball jig of FIGURE 1 with the ball-holding means in a different position;

FIGURE 3 is a top plan view of the jig of FIGURE 1;

FIGURE 4 is a side elevational view of the left side of the jig of FIGURE 1; and

FIGURE 5 is a fragmentary sectional view taken on the line 5—5 of FIGURE 1.

2

Referring to FIGURE 1 a bowling ball jig 10 embodying the principles of the present invention is shown as including, as its major component, a frame 12, a ball retainer 14 for holding a bowling ball 15, a tilt yoke 16 on which the frame 12 is mounted, and a horizontal support 18 on which the tilt yoke 16 is mounted for lateral sliding movement.

The frame includes a horizontal base plate 20 and a pair of spaced vertical brackets 22 secured thereto in any suitable manner as by welding or bolting. Conveniently, the brackets may be somewhat trapezoidal in shape as seen in FIGURE 4 and are rigidly constructed of metal. Conveniently, both the upright portions and the horizontal top and bottom portions may be lengths of angle iron 10 suitably joined as by welding. Depending from the lower surface of the plate 20 are two spaced rectangular mounting brackets 24 having opposing arcuate slots 25 cut therein. As seen in FIGURE 4, slots 25 are concave downwardly and are formed with a radius of curvature equal to the radius of the ball 15.

The frame is supported on a pair of bolts 26 which pass through the slots 25 and through a pair of spaced tilt yoke brackets 28. As seen in FIGURES 1 and 4 the heads 30 of the bolts engage the outer surface of the left tilt yoke bracket and the threaded ends pass through the right tilt yoke bracket. The threaded end of one bolt is provided with a conventional nut 32 and the end of the other bolt is provided with an internally threaded tightening handle 34. The bolt having the handle 34 is also provided with a nut 36 engaging the inner surface of mounting bracket 24 whereby rotation of the handle clamps or unclamps the mounting bracket 24 between the nut 36 and tilt yoke 28.

The lower edge of each tilt yoke bracket 28 is provided with a transverse flange 38 which is slidably retained in a track 40 which extends parallel with the tilt yoke bracket. The tracks 40 are rigidly connected to each other by any suitable means such as pieces 42. To the right of the tilt yoke brackets and secured to one of the pieces 42, as by welding, is a vertical bracket 44 through which a horizontal, threaded rod 46 passes. The bracket 44 is provided with a threaded insert 48 engaging the rod 46 whereby rotation of the rod, as by means of a handle 50 at its outer end, causes the rod to translate with respect to the bracket 44. The inner end of the rod 46 is journaled in a vertical plate 52 which extends between and is secured to the tilt yoke brackets 28 whereby the tilt yoke 16, the frame and the cradle 14 translate with the rod 46. The rod may be connected to the plate 52 in any suitable manner as by means of a washer 51 and a cotter pin 53.

The front tilt yoke bracket 28 is provided with an upper vertical pointer 54 secured to the upper front surface thereof for indicating the amount of tilt on a scale 56 secured to the upper surface of the base 20. A lower vertical pointer 55 is similarly fixed to the lower front surface for indicating the extent of lateral movement of the tilt yoke 16 and associated elements on a scale 57 secured to the top of the front track 40.

60 The ball retainer 14, as shown, includes three arcuate metal strips and a horizontal split ring 58 secured together, as by welding, to form a basket-like structure. A single substantially hemispherical strip 60 is secured at its ends to the lower edge of the split ring, and two shorter arcuate strips 62 are secured transversely to the strip 60 and to the lower edge of the split ring 58 so as to form a continuous ball-engaging inner surface. The split ring 58 is releasably engageable with the circumference of the ball 62 by means of a latch 64 which in the closed position 65 (FIGURES 1 and 2) pulls the ends of the split ring together. In the open position (FIGURE 3), the latch permits the ring to expand slightly. As shown, the latch is 70

of the quick release type which includes a handle 66 pivoted at one end to the split ring near one of the ends of the ring, as by means of a bracket 68, for movement in the plane of the ring. A link 70 is pivoted to the opposite end of the ring as by means of a bracket 72 and to the shank of the handle intermediate the ends thereof.

The ball retainer is mounted for rotation in a vertical plane about an axis through the center of the ball 15 by means of a pair of trunnions 74 secured to the exterior of the ring 58 at opposite locations and extending laterally thereof. Conveniently, a boss 76 may be first secured to the ring on opposite sides and the trunnions 74 then secured to the bosses. Each trunnion is rotatably supported by and passes through the lower end of a vertical radius link 78 and then passes through the adjacent bracket 22 to terminate in a threaded portion 80. As seen in FIGURE 4, each bracket 22 is provided with a vertical plate 82 secured thereto and having an upwardly concave, arcuate slot 84 therein which has a radius of curvature equal to the radius of the ball 15. As seen in FIGURE 3, the trunnions 74 pass through and are slidably forwardly and rearwardly in the slots 84.

The threaded portion 80 of the left trunnion 74 is provided at its extremity with an interiorly threaded lock arm 86 and with a collar 88 between the lock arm and the plate 82 whereby tightening the lock arm clamps the trunnion against rotational or sliding movement. The extremity of the right trunnion is provided with a suitable handle 90 for manually rotating the ball retainer 14. Between the handle 90 and the plate 82 are a lock arm 92 and a loosely fitting collar 94 for clamping the trunnion in the same manner as arm 86 and sleeve 88.

As seen in FIGURE 3 means are provided for adjustably sliding the trunnions 74 in slots 84. As shown, a horizontal threaded rod 96 is threaded through a bracket 98 which is secured to the side of the right bracket 22. The forward end of the rod 96 has a handle 100 thereon for manually rotating the same, and the rear end of the rod has a small ball 102 thereon which is retained loosely in a socket 104 in the periphery of collar 94.

The radius links 78 are pivoted for rotation fore and aft about an axis flush with the top of the ball 15. As seen in FIGURES 1 and 4 plates 106 are secured to the upper portion of the upright brackets 22 and are provided with apertures having a common axis which touches the top of the ball 15. Trunnions 108 secured to the radius links pass through the apertures and are rotatably retained therein as by nuts 110 and washers (not shown).

A strengthening ring 112 of substantially hemispherical shape may be secured at its ends to the lower portion of the radius links 78, as seen in FIGURE 3, to lend added rigidity to these elements. As seen in FIGURE 5 the upper end of the left link 78 terminates in a depending pointer 114 which registers the span distance on a scale 116 secured to and rotatable with the ball retainer 14. As shown, the scale 116 is a thin arcuate strip having graduations 118 in the inner vertical surface thereof and is secured to boss 74 by means of a rigid arm 120. A scale 122 having graduations 124 for indicating pitch in a fore and aft direction is secured to the outer vertical surface of plate 82. An indicator mark 126 on the outer surface of the left radius link 78 registers with the scale 122.

In order to use the jig for drilling thumb and finger holes in a bowling ball, each of the pointers 54, 55, 114 and 126 is adjusted to the center graduation of its scale (which for convenience may be labeled "0") and the jig is then fixed in place below a vertical drill 128 such that the axis of the drill passes through the center of the ball 15 which has been clamped in the ball retainer 14 by means of latch 64.

In order to drill a hole having a pitch in a fore or aft direction, handle 100 is rotated so as to slide trunnions 74 in slots 84 whereby the ball 15 is rotated fore or aft about an axis along the top of the ball. The direction and extent of pitch will be indicated on scale 122 by pointer 126. When the pointer 126 indicates "0," the

fore or aft pitch will be zero and thus a hole formed by the drill 128 will have an axis through the center of the ball 15. The direction and extent of the pitch of the hole to be drilled will be indicated by the direction and magnitude of the movement of pointer 126 from "0" on scale 122.

To drill a hole having a pitch in a lateral direction, handle 34 is loosened, the frame 12 and ball retainer 14 are manually tilted laterally in the desired direction and extent indicated by pointer 54 on scale 56, and handle 34 is tightened. Handle 50 is then rotated to move the tilt yoke 16, ball retainer 14 and frame 12 laterally so as to return the ball 15 to a position at which the drill 128 will enter the surface of the ball at the preselected location. When the pointer 54 indicates "0" on scale 56, the drill will form a hole which has no lateral pitch and which has an axis through the center of the ball provided that the pointer 55 indicates "0" on scale 57. The direction and extent of the lateral pitch of the hole will be indicated by the direction and magnitude of the movement of pointer 54 away from "0" on scale 56. FIGURE 2 illustrates the position of the frame 12 and tilt yoke 16 for drilling a hole having a lateral pitch.

To drill two holes having a preselected span between them, handles 86 and 92 are loosened, the ball-retainer 14 is rotated, a preselected extent by means of handle 90 and handles 86 and 92 are tightened. Conveniently the preselected span distance is divided by two and each half span is measured in opposite directions from zero on scale 116 by pointer 114. When one hole is drilled at each of the two indicated half spans, the two holes will have the correct span between them.

Thus, it is apparent that the apparatus of the present invention permits thumb and finger holes of any span, fore and aft pitch and lateral pitch to be drilled in a bowling ball without changing the position of the ball in its retainer 14. Further, the apparatus is readily adjusted with a minimum of manual movements and exposes a maximum of working ball surface. While a specific embodiment of the jig has been described, it is apparent that modifications may be made therein, and the details thereof are not intended to be limiting except as they appear in the appended claims.

What is claimed is:

1. Apparatus for adjustably positioning a spherical object comprising: a frame; means within said frame for supporting a spherical object; means mounting said supporting means within said frame for rotation about a first axis coinciding with a horizontal diameter of the object; means mounting said supporting means within said frame for rotation about a second axis parallel to and positioned above said first axis; means mounting said frame for rotation about a third axis transverse to said first and second axes and positioned below said first axis; and means for moving said frame linearly in a direction transverse to said third axis.

2. Apparatus as in claim 1 wherein said means for supporting the object includes: a single narrow split ring having a diameter substantially that of the object, a latch for drawing together the ends of said split ring and thereby engaging the object around its largest circumference, and means fixed with respect to said ring for supporting the object from below and for positioning the same with respect to said ring.

3. Apparatus as in claim 2 wherein said latch includes a first member pivoted near one end to one end of said split ring and a second member pivoted at one end to said first member intermediate the ends thereof and engageable at its other end with the other end of said split ring.

4. Apparatus for adjustably positioning a spherical object which comprises: first and second horizontally spaced frame members; a link depending from each of said first and second frame members; clamping means for releasably engaging the spherical object around a narrow continuous horizontal portion thereof thereby leaving a substantial

portion of the object exposed, said clamping means being positioned between said links; a shaft extending from each of two diametrically opposite points on said clamping means and extending along a first axis which passes through the center of an object in said clamping means, said shafts being rotatably supported by said links; said links being rotatably supported above said shafts by said members for rotation about a second axis which is parallel to said first axis and spaced above said first axis a distance equal to a radius of the object; support means below said clamping means for said frame members; means mounting said frame members for rotation about a third axis which is transverse to said first and second axes and which is positioned below said first axis; and means mounting said support means for linear movement in a direction parallel to said first axis.

5. Apparatus as in claim 4 further comprising means for adjustably rotating said links about said second axis.

6. Apparatus as in claim 4 wherein said means for mounting said frame for rotation about a third axis includes means having a downwardly concave slot therein and means fixed with respect to said frame and slidable in said slot.

7. Apparatus as in claim 6 wherein the radius of curvature of the downwardly concave slot is equal to a radius of the object.

8. Apparatus as in claim 4 further comprising means for releasably clamping one of said shafts to one of said frame members whereby rotation of said object clamping means about said first axis and said second axis is prevented simultaneously.

9. Apparatus for adjustably positioning a spherical object which comprises: first and second horizontally spaced frame members; object-retaining means for engaging the object only around its largest circumference and below its largest circumference thereby exposing substantially the entire upper half of the object; a shaft extending from each of two diametrically opposite points on said clamping means and extending along a first axis which passes through the center of an object in said retaining means, each of said shafts being mounted for rotation in the lower end of a link and passing through an aperture in one of said frame members; means pivoting the upper ends of said links to said frame members for rotation about a second axis parallel to said first axis; means threadedly engaging the end of one of said shafts for locking said one shaft to one of the frame members; an upstanding bracket lying in a plane parallel to said first axis and having a downwardly concave slot therein; a pair of spaced elements slidable in said slot and fixed with respect to said frame members below said retaining means; means for releasably clamping said elements to said bracket; track means parallel to said bracket and slidably retaining said bracket.
